UNITED STATES PATENT OFFICE.

JAMES M. BRAZILL, OF ROCHESTER, NEW YORK.

STAIRWAY FOR FIRE-ESCAPES, &c.

No. 878,863.

Specification of Letters Patent.

Patented Feb. 11, 1908.

Application filed June 3, 1907. Serial No. 377,113.

To all whom it may concern:

Be it known that I, JAMES M. BRAZILL, a citizen of the United States, and a resident of Rochester, in the county of Monroe and 5 State of New York, have invented an Improved Stairway for Fire-Escapes and Similar Purposes, of which the following is a specification.

This invention relates to that class of fire 10 escapes in which an outside stairway is made use of, such stairway connected to the walls of the building and supported therefrom and extending from the upper story to a point practically on a level with the first floor above 15 the ground floor of the building, and pertains more especially to a stairway leading from such lower platform to the ground.

The object of my present invention is to provide a stairway for connecting such a 20 lower platform of a fire escape with the ground which shall be free from the many objections found in such stairways as heretofore constructed. Such stairways have usually heretofore been arranged to either 25 slide vertically upon suitable guides and balanced by suitable counterweights so that a downward pressure exerted upon the stairway itself would force the same downwardly until it reached the ground and was in operative position connecting the lower platform to the ground,—or such stairways have been 30 hinged at their upper end to the platform and arranged to be swung on such hinged connection upwardly and outwardly far enough to be out of the way of pedestrians 35 on the street. To this latter arrangement there are serious objections in that it requires considerable space along the side or front of the building where the fire escape is located, 40 and when such hinged stairway is swung downwardly so as to occupy practically a horizontal position a very heavy weight is required to counterbalance it and this same objection obtains in regard to the amount of 45 the counterweight of that class in which the stairway is arranged to slide vertically upon suitable guides. These objections I have overcome in the construction herein shown and described consisting essentially of a stairway 50 comprising two sections, the upper section pivotally connected to the lower platform and arranged to swing outwardly and upwardly on such pivotal connection and with the lower section arranged to slide longitudinally upon the upper section whereby 55 the distance required in which to swing the

entire stairway may be reduced one half. A similar reduction results also in the distance which the lower section has to slide upon the upper section and still again a similar reduction results in the amount of travel of the free end of the entire stairway and also of the rope or preferably wire cable, by means of which the counterweight is connected thereto. In this construction also the stairway may be swung on its pivot so as to occupy a vertical position when out of use and that too while occupying only one half of the space vertically which would be required for a stairway as usually constructed in one section.

In the accompanying drawings I have shown my present invention as applied to a fire escape of substantially the style or pattern shown in a former patent of mine issued 75 September 2, 1902, and numbered 708120, although, however, I wish it understood that I do not limit myself to the application of my present invention to any particular style of fire escape.

Such drawings are as follows:—Figure 1 is a face view of such a fire escape as mentioned with my stairway connected thereto and shown as in its operative position leading from the lower platform to the ground. Fig. 2 is a side view of the parts as seen in Fig. 1. Fig. 3 is a side view of the lower platform only of such a fire escape showing my stairway with the lower section thereof as having been moved part-way upwardly on the upper section. Fig. 4 shows the parts seen in Fig. 3 and with the lower section moved to its final position relatively to and on the upper section and with the upper section moved outwardly and upwardly to practically a 90 horizontal position. Fig. 5 shows the parts as seen in Figs. 3 and 4 and with my stairway moved to its final inoperative position. Fig. 6 is an enlarged detail view of the supporting and guiding rod connections for my 100 stairway. Fig. 7 is an enlarged detail view of the lower platform connection to the stairway. Figs. 8 and 9 are side and face views respectively of the upper end of one of the sides or string pieces of the lower section of my stairway showing details in the construction thereof as will be explained.

Similar letters refer to similar parts throughout the several views.

Referring to the drawings,—P is the lower 110 and P' the upper platform of a fire escape constructed in accordance with my United

States Patent No. 708120, dated September 2, 1902, and a , a^1 , a^2 and a^3 are the four vertical members of angle iron constituting the outer supports for the several platforms and 5 for the stairways connecting such platforms. Articulating with ears o secured to the lower platform P and projecting outwardly therefrom is seen the upper section U of my stairway proper. This upper section U of my 10 stairway consists, as indicated, of side or string pieces u u , two on each side connected by tread supports s of the usual angle iron and upon such tread supports there are secured the usual treads or steps s^1 . The upper and lower string pieces u u on each side of this stairway are connected at their upper ends by suitable plates b and at their lower ends also by plates b^1 . These plates b have 15 holes therein by means of which they articulate upon a bolt passing through a suitable hole therefor in each one of the ears o projecting outwardly from the frame work of the fire escape opposite the lower platform P . Curved guide rods g are secured to the 20 plates b at their upper ends and also to the plates b^1 at their lower ends, one on each side of the stairway U . These guide rods g are located a slight distance above and run parallel with the string pieces u of the upper section of the stairway U , and the lower ends of 25 these guide rods g are carried around under and beneath the upper section U of my stairway, and on these guide rods there is arranged to slide the supporting rod n having 30 eyes or loops formed at its ends to receive and slide upon such guide rods g , which in turn are bent inwardly at their ends and secured on the inside of the plates b and b^1 . This rod n is secured in the upper end of the 35 lower section L of my stairway in the following manner, viz: As shown in Figs. 8 and 9, the side or string pieces l l on each side of this lower stairway are connected at their upper ends by plates f and in these plates f 40 there are seen slots, which, coöperating with notches in the upper edge of the lower string pieces l l , serve to retain this rod n revolvably in its position near the lower edge of the lower stairway L and at its upper end. 45 This lower stairway L is constructed substantially in the same way as the upper section U and has the side or string pieces l l having connecting pieces f at the top and f^1 at the bottom on each side, and to this lower 50 stairway L there are secured the hooks v projecting upwardly and rearwardly and operating in the manner to be explained, to retain the lower section L of my stairway in its proper position when folded up and out of 55 use. The proportion of the parts thus far described is such as to permit of the lower stairway being slid outwardly and upwardly upon the upper section U , in the manner indicated in Fig. 3, from which position it may 60 be still further moved so that the upper and

lower stairways occupy positions relatively to each other, such as indicated in Figs. 4 and 5. Guide rods e are suitably supported, by means of ears c c , upon the vertical members a and a^4 , as indicated in Figs. 1 and 2, and 70 upon these guide rods e there is arranged to slide a cross head consisting in the plates h and h^1 suitably secured together, as indicated in Fig. 6, by the ring bolts t articulating with the upper ends of the links t t . These links 75 t t articulate at their lower ends with suitable bolts therefor in the plates b^1 , at the lower end of the upper section U of my stairway. The length of these guide rods e between 80 their supports is such as to permit of the upper section U of my stairway being raised to the position indicated in Fig. 5, in which position it is held by means of a suitable weight w having a cord r attached thereto working over suitable pulleys x x supported at the top 85 of the frame work of the fire escape and connected to the bent plate h of the cross head constituted by plates h and h^1 and arranged to slide upon the guide rods e in the manner already described and clearly indicated in 90 Figs. 1, 2 and 6. Sleeves e^1 e^1 are seen at the lower ends of rods e e to support the plate h^1 above the ears c c . 95 Attention is especially called to the curved lower ends of the guide rods g whereby the lower section L of my stairway, when it is permitted to slide down upon such rods, is caused to assume the position indicated in Figs. 1 and 2 so as to constitute with such 100 upper section U of the stairway a continuous 105 stairway from the platform P to the ground. Attention is also called to the fact that owing to the tendency of a moving body to continue its motion in a straight line and also to the further tendency of such a body when 110 deflected from such course by contact with any other body at a point outside of its center of gravity, to simultaneously rotate upon an axis passing through its center of gravity, the 115 action of the lower section of my stairway in sliding down from the upper section to its operative position with its lower end upon the ground, is as follows:—Such lower section, just prior to its reaching the ground and owing to the curved construction of the lower 120 end of the guide rods g , is caused to swing nearly upon its center of gravity and its center longitudinally in such a way, that, as its upper end assumes its normal operative position in alinement with the upper section 125 of the stairway U , its lower end is forced upwardly and outwardly so as to break the force of the fall of the lower section L and cause it to strike the ground, pavement or sidewalk with very little force, and then such 130 lower section of my stairway, swinging upon its supports consisting in the rod n and the lower ends of the curved rods g , drops into its normal position, with its lower end resting upon the ground, with very little force. The 130

hook *v*, seen at the lower end of the lower section *L* of my stairway, when the parts are moved to the position indicated in Fig. 5, serve to prevent such lower section *L* from 5 swinging inwardly into the body of the fire escape by engaging the lower tread of the upper section *U* in the manner indicated in Figs. 4 and 5.

To provide hand rails adapted to be engaged by the hand of one passing up or down 10 the stairway where the links *t* are not available, I make use of the rods or bars *i* having eyes formed in their curved upper ends encircling and adapted to slide on the rods *t*. 15 These rods *i* are curved near their lower ends, as indicated, and have at their extreme lower ends eyes formed thereon by means of which they articulate upon suitable bolts or screws threaded to the bottom plates *f*¹ of the lower 20 stairway. These rods *i*, when the stairway is in its operative position, as indicated in Fig. 2, are engaged by the clips *d* secured to the string pieces *l* on each side of the lower section *L* of the stairway and are thereby 25 held against displacement. Adjustably secured upon the links *t* are seen collars *j* adapted to engage under and sustain the upper ends of the rods *i*.

The several positions for the rods *i* are 30 shown in Figs. 1, 2, 3, 4 and 5 for the corresponding positions of the sections of my stairway herein indicated. The collars *j* may be so adjusted as to sustain the lower 35 stairway *L* in operative position even should the lower end thereof not extend quite to the ground or pavement, and in this case of course the rods *i* should be of sufficient size to normally retain the curvature and conformation thereof, as indicated in the drawings. 40

When my stairway is out of use, the parts are moved to the position indicated in Fig. 5 where they may be securely held by means of a moderate weight *w*, owing to the fact 45 that very little effort is required to retain such parts in such a vertical position, the weight of the stairway being carried by its pivotal support at the lower end of the system when in that position and located opposite the lower platform *P*. 50

In case of fire or when for any other reason it is desired to use the stairway, the operator upon reaching the platform *P* pushes outwardly upon the two sections of the stairway, forcing them from the position indicated in Fig. 5 very nearly to the position indicated in Fig. 4 when the weight of the parts causes them to assume successively the positions indicated in Figs. 3 and 2. When 55 it is desired to fold the stairway up, the lower section *L* thereof is moved outwardly and upwardly upon the upper section *U* to the position indicated in Fig. 3 by a person standing upon the ground and held there, 60 while at the same time an operator, standing

upon one of the upper platforms *P*¹ of the fire escape, by pulling downwardly upon the rope *r* will cause the parts to assume the positions indicated in Fig. 5 in which positions the weight *w* will securely retain them. 70

The face of the wall of the building to which my fire escape is attached is represented in Fig. 2 by the vertical line at *W*. When my stairway is in its operative position, as indicated in Figs. 1 and 2, the connecting links *t* and also the rods or links *i* 75 constitute hand rails readily within the reach of a person descending upon the stairway.

The inner edges of the horizontal members of the ears *c* may be provided with notches, 80 not shown, for engaging and holding the links *t* to prevent their rattling when my stairway is in its inoperative position.

What I claim is:—

1. A stairway for fire escapes and similar 85 purposes comprising; an upper section and a pivotal support therefor; a lower section arranged to slide over on to and practically parallel with such upper section and means for holding such upper section in a vertical 90 position on such pivotal support with such lower stairway adjacent thereto and parallel therewith.

2. A stairway for fire escapes and similar 95 purposes comprising; an upper section and a pivotal support therefor; a lower section arranged to slide over on to and practically parallel with such upper section; connecting links articulating with such upper stairway at its lower end; suitable guiding mechanism for the upper ends of such links and means connected to such links for holding such upper stairway in a vertical position resting on such pivotal support and with such lower stairway adjacent thereto and 100 parallel therewith.

3. A stairway comprising; two sections, one arranged to slide upon the other and the lower section arranged to slide downwardly upon the upper section so as to permit its 110 lower end to reach a suitable platform and means for lessening the impact of such lower section against such platform comprising means for moving the lower end thereof outwardly and upwardly just before reaching such platform.

4. A stairway for fire escapes and other similar purposes comprising; an upper section; a pivotal support therefor at its upper end; a lower section arranged to slide longitudinally upon such upper section and means for lessening the impact of the lower end of such lower section against its support when in operative position comprising means for moving such lower end of such lower section outwardly and upwardly just prior to its reaching such support. 120

5. A stairway; comprising two sections the one arranged to slide upon the other, the lower section arranged to slide downwardly 130

upon the upper section so as to permit its lower end to reach a suitable platform and means for moving the lower end of such lower section outwardly and upwardly just before 5 reaching such platform, such means comprising guide rods connected to such upper stairway and arranged to deflect the upper end of such lower stairway downwardly into alignment with the lower end of such upper 10 stairway.

6. In a stairway for fire escapes and other similar purposes; means for guiding the stairway obliquely downwards so that its lower 15 end may rest upon a suitable support and means for moving the lower end of such stairway outwardly and upwardly just before reaching such support.

7. In a stairway for fire escapes and other similar purposes; means for guiding the 20 stairway obliquely downwards so that its lower end may rest upon a suitable support and means for moving the lower end of such stairway outwardly and upwardly just before reaching such support, such means comprising 25 suitable guiding mechanism for the upper end of such stairway operating to deflect such upper end downwardly just before the lower end of such stairway reaches such support therefor.

30 8. In a stairway for fire escapes and similar purposes comprising two connected sections; a pivotal support for the upper end of the upper section of such stairway; a pair of links articulating with the lower end of the 35 upper section of the stairway; a suitable support for the upper end of such links adapted to retain the same with such stairway in either its operative or inoperative position; a second pair of links pivotally connected to the lower stairway near its 40

lower end and adapted at their upper ends to slide upon such first named links.

9. In a stairway for fire escapes and similar purposes comprising two connected sections; a pivotal support for the upper end of the 45 upper section of such stairway; a pair of links articulating with the lower end of the upper section of the stairway; a suitable support for the upper end of such links adapted to retain the same with such stairway in either its operative or inoperative position; a second pair of links pivotally connected to the lower stairway near its 50 lower end and adapted at their upper ends to slide upon such first named links, such upper and lower links adapted to sustain the stairway in operative position independently of any other support for the lower end of either 55 of such sections thereof.

10. In a stairway for fire escapes and similar purposes comprising two connected sections; a pivotal support for the upper end of the upper section of such stairway; a pair of links articulating with the lower end of the upper section of the stairway; a suitable 60 support for the upper end of such links adapted to retain the same with such stairway in either its operative or inoperative position; a second pair of links pivotally connected to the lower stairway near its 65 lower end and adapted at their upper ends to slide upon such first named links connected to the lower end of the upper stairway, such links adapted to serve as hand rails for the 70 stairways.
